United States Patent Office.

JACOB GETTEMY, OF DONEGAL, PENNSYLVANIA.

Letters Patent No. 72,476, dated December 24, 1867.

TIRE-BENDING AND SHRINKING MACHINE.

The Schedule referred to in these Letters Patent and making part of the same.

TO ALL WHOM IT MAY CONCERN:

Be it known that I, JACOB GETTEMY, of Donegal, in the county of Westmoreland, and State of Pennsylvania, have invented a new and improved Tire-Shrinking Machine; and I do hereby declare that the following is a full, clear, and exact description thereof, which will enable others skilled in the art to make and use the same, reference being had to the accompanying drawings, forming part of this specification, in which—

Figure 1 represents a vertical longitudinal section of my improved tire-shrinker, the plane of section being indicated by the line x x , fig. 2.

Figure 2 is an inverted plan view of the same.

Figure 3 is a side elevation of the same, showing it on a reduced scale.

Similar letters of reference indicate like parts.

This invention relates to an adjustable tire-shrinker, which can be set to bend the tires to fit different wheels, and which is so arranged that it will require but very little power to bind tires of great strength and thickness.

The invention consists in arranging three revolving drums, of which one is fitted in a stationary frame, while the other two are arranged in sliding frames on either side of the other roller. The upper edges of the side rollers are higher than the lower edge of the central roller, and by moving the side rollers on inclined planes, this distance may be varied at will. A metal bar, which is placed upon the side rollers, and below the central roller, will, when the former are raised, and moved towards the central roller, be bent, until it forms the necessary curve, which can be ascertained by an indicator with which the device is provided.

A represents a frame of suitable dimensions, and made of suitable material, of sufficient strength for supporting and holding the other parts of this machine. It consists of two side boards, a a , and end-pieces b b , which are joined in any suitable manner. From the side boards project uprights c c , in which bearings for a horizontal shaft, B , are arranged, on which a corrugated roller is formed, as shown. In a vertical line below the roller B , and parallel with the same, is arranged in the frame A another horizontal shaft C , which has cranks, (or a crank-wheel,) d , that are connected by means of rods e e with frames D D . The cranks on the shaft C being exactly opposite to each other, and of equal length, and the bars e e being also of equal length, the frames D D are always held in positions corresponding to each other, as regards their distance from the roller B , and as regards their level. The frames D D are fitted in inclined grooves f f , which are formed in the sides of the frame A , as is clearly shown in fig. 1, said grooves being gradually higher, the nearer they are to the roller B . It will be seen that by turning the shaft C , the frames D will be simultaneously moved towards or from the roller B , in the grooves f . A horizontal roller, E , is hung in each of the frames D , as shown. A ratchet-wheel or wheels, F , are mounted on the shaft C , and a pawl or pawls, G , are fitted on another horizontal shaft, H , so as to be easily thrown into the wheels F ; thereby the shaft C will be prevented from turning in that direction in which the rollers E would be moved apart. The shaft H is provided with a crank or handle, g , by means of which the pawls G can be operated at pleasure. The shaft C is also provided with a handle or crank, or is provided with some mechanism by which it can be turned in either direction. The shaft B is also provided with a crank or handle, to allow it being turned.

The operation is simple, and as follows: The tire is placed upon one of the rollers E , and moved under the roller B . The latter is then turned, and, being corrugated, it will be able to carry the tire forward until the same rests upon both rollers E E , being depressed in the centre by the roller B . Then the shaft C is turned in the direction indicated by the arrow in fig. 1, whereby the rollers E will be moved with the frames D in the grooves f , towards the roller B , and will at the same time be raised, (on account of the inclined grooves,) thereby gradually bending the tire more and more. The pawls G at the same time prevent the tire from holding the rollers E E back, or from pushing them back and down. When the tire has been sufficiently bent, it can be fed along between the rollers, and shrunk, while thus fed, until finished. A hand or pointer, i , is secured to one end of the shaft C , and moves over a circular or semicircular dial, j , while the shaft is being turned. On the dial are marks, which denote the diameter of the circle formed by the tire while the parts are in any one position. The exact curve of the tire can thus be easily obtained.

What I claim as new, and desire to secure by Letters Patent, is—

1. The device for operating the rollers E E, so that they may be moved in the desired direction, said device consisting of the crank-shaft C, in combination with the connecting-rods e e, sliding frames D D, and grooves or guides f, in frame A, all made and operating substantially as herein shown and described.
2. The device set forth in the foregoing claim, in combination with the indicator i on shaft C, the same being made as set forth.
3. The indicating-device i, in combination with the roller B, arranged as set forth.
4. The roller B, when corrugated as set forth, in combination with the rollers E E, the latter travelling on inclined planes, substantially as and for the purpose herein shown and described.

JACOB GETTEMY.
